Letter Patent No. 2386, Dated Aug. 14, 1866

Design for Coffin Stirrings.

The schedule referred to in this Letter Patent, and making part of the same,

To all whom it may concern,

Be it known that S. D. D. Arnold of New Britain
Hartford County and State of Connecticut have invented a new
Design for Stirrings to be used on Coffins and other Burial Cases;
and I do hereby declare that the following is a full, clear, and exact
description thereof, which will enable others skilled in the art
to make and use the same, reference being had to the accompa-
nying drawing forming part of this Specification.

The Design embraced in the present invention con-
sists of an ornamental plate to be used upon the sides or the top,
or any other desired portion of a coffin or other burial case
and in the accompanying plate is illustrated the

Figure of which is a photographic view.

A, in the plate represents a hand, in and by the fingers of
which, a stem C, is grasped having a series of rose leaves D
a center rose B, and rose buds E, about and over the upper
edge of the rose B.

I claim as new and desire to secure by Letters Patent
The Design herein described, and shown in the accompa-
nying plate of illustration.

Witnessed

Chas Peck.
